SWAGING TOOL

Otto J. Bratz, Adrian, Mich., assignor to American Chain & Cable Company, Inc., New York, N. Y., a corporation of New York

Application June 6, 1940, Serial No. 339,037

6 Claims. (Cl. 140—113)

This invention relates to a hand operated metal working tool and more particularly to a swaging tool for applying a fitting to a member such as an elongated member and has been shown as adapted to apply a spherical fitting to a strand, cable or rope.

Among the objects of this invention are improvements in hand operated metal working tools more particularly for applying a fitting on a cable or the like or for applying a connector to adjacent ends of cables or the like and which is of such light weight as to be portable and which has provision for adjustments so that the swaging or other metal working operation may be performed in several stages.

Other objects of the invention will appear from the following description taken in connection with the drawing in which,

Fig. 1 is a side elevational view of the swaging tool showing parts broken away and parts in section;

Fig. 2 is a central longitudinal vertical section through the body of the tool partly broken away to show operating parts in side view;

Fig. 3 is a longitudinal horizontal section through the body of the tool on the line 3—3 of Fig. 2 showing operating parts in top plan view;

Fig. 4 is a vertical section on the line 4—4 of Fig. 2; and

Fig. 5 is a longitudinal horizontal section through the dies showing their position at the end of the swaging operation.

The swaging tool comprises a body 6 of the general shape disclosed in Fig. 1 provided with a lower body handle 7 and an upper operating handle 8 and has been illustrated for purposes of disclosure only as a means for applying a spherical fitting on the end of a cable.

The body 6 is provided at its front end with a longitudinally extending cylindrical bore 10 to receive the dies 11 and 12 and with a transversely extending slot 13 open at the top to receive a cable 15 and a spherical blank or fitting 16 and terminating at a point slightly below the centers of the semi-spherical die faces 17 and 18 of the dies 11 and 12 so that the cable with the blank on it may be placed in position on the die face 17 of the die 11 and the cable rest on the bottom wall of the slot 13. The dies are provided with transversely extending grooves 19 and 20 to receive the cable as is understood.

The upper face of the stationary die 11 is provided with a recess 25 into which projects a set screw 26 to lock the die in the proper angular position so that its groove 19 extends horizon-

tally. Secured in the outer end of the cylindrical opening 10 is a die backer in the form of a threaded stud 30 which also clamps a U-shaped cable supporting bracket 31 against the end of the block. The legs of the cable supporting bracket are provided with slots 32 and 33 in alignment with the slot 13 in the body portion 6 and of a width equal to the diameter of the cable and the lower ends of the slots are provided with half round right angularly related extensions 34 and 35 of the same diameter as the diameter of the cable and in alignment with the groove 19 and in the die block 11, the lower edges of the extensions being alined with the bottom wall of the slot 13 in the body to support the cable.

The cable supporting bracket also acts as a retaining abutment for a return spring 36 operating on a plunger 37 bearing on the movable die 12 to move the die 12 into the open position in Fig. 1.

The upper operating handle 8 extends into a socket in a slidable pivoted cam head 40 in which it is secured by a rivet pin or the like. The head 40 is provided with a narrow portion 41 which operates between inwardly extending opposed flanges 42 and 43 on the upper edges of shoe plates 44 and 45 secured to the body portion by screws 46 as indicated in some of the figures. This head is of the general form shown in the figures and its depending portion 50 is provided with a wide bearing portion 51 carrying a pivot pin 52 operating in slots 54 and 55 in the shoe plates 44 and 45. This wide portion provides shoulders cooperating with the opposed flanges 42 and 43 to limit the opening movement of the operating handle 8. The forward end of this wide portion is provided with a cylindrical face 60 bearing in a concave seat 61 in the rear end of the movable die 12, and alining the groove 20 of the movable die 12 with the groove 19 of the stationary die 11.

The rear end of the enlarged portion 51 is provided with an arcuate eccentric cam face 62 co-operating with a backer roller 63 supported by a leaf spring 64 secured to the body portion by means of a bar plate 65 tenoned in the shoe plates 44 and 45. The backer roller is retained in position by a bar plate 66 tenoned in the shoe plates as shown.

The roller cooperates with a roller backer block 70 provided with rectangular guide lugs 71, 72, operating in horizontal slots in the shoe plates. The roller backer plate is held in place by an adjustment screw 74 by means of which

it may be adjusted in the slots in the shoe plates to control the forward limit of movement of the movable die during its forward movement. This adjustment screw is rotated by means of the lower handle 7 to which it is secured by a transversely extending pin 15. The front face of the roller backer is arcuate and substantially concentric with the pivot pin 52 so that the cam face on the rear of the head 51 operating on the roller will cam the head and move the die 12 forward to swage and compress the end fitting on the cable.

In the use of the swaging tool, the lower handle 7 is rotated to control the operated position of the movable die in accordance with the amount of reduction desired to be effected during the first series of swaging operations. The dies are then separated and the cable with the blank fitting on it is passed through the slots 32 and 33 of the cable supporting bracket 31 into the extensions 34 and 35 of these slots and the blank fitting is seated in the die face 17 of the stationary die 11. These dies are closed and opened and the cable is rotated until the dies have operated at the required number of different points circumferentially of the fitting after which the lower handle is turned clockwise as viewed from the right of Fig. 1 to advance the roller backer 78, the head 51 of the upper handle 8 and the movable die 12 after which a second series of operations is performed as before and so forth and for the last series of operations the roller backer is advanced to cause the movable die to engage the stationary die at the limit of its forward movement.

It is obvious that this invention is not limited to the shape of the faces of the dies and that these faces may be given any desired shape depending upon the original and/or desired final cross sectional shape of the fitting or the shank of the fitting and that a swaging tool built in accordance with this invention may be used to apply fittings not only to an end but also at any point along the length of a cable or any other elongated member and to connect any member to or about another member regardless of the relative axial dimensions or lengths of the members and to change the cross sectional shapes of, and perform other operations on, articles of various kinds.

While I have described a preferred form of my invention, it is to be understood that this has been done for the purpose of disclosure only and that I reserve the right to make such changes as fall within the principle of the invention disclosed and the scope of the appended claims.

I claim:

1. A swaging tool comprising a body portion provided with a handle, a fixed die supported in said body portion, an opposed movable die supported in said body portion, a roller supported in said body portion, a cam between said roller and said movable die, and a handle for operating said cam, said roller being supported for rolling movement with said cam and a spring normally pressing said roller into its home position.

2. A swaging tool comprising a body portion provided with a handle, a fixed die supported in

said body portion, an opposed movable die supported in said body portion, a roller supported in said body portion, a cam between said roller and said movable die, and a handle for operating said cam, said roller being supported for rolling movement with said cam, a spring normally urging said roller into its home position, and means on said body portion stopping the roller in its home position.

3. A swaging tool comprising a body portion provided with a handle, a fixed die supported in said body portion, an opposed movable die supported in said body portion, a roller supported in said body portion, a cam between said roller and said movable die, a handle for operating said cam, said roller being supported for rolling movement with said cam, a spring normally urging said roller into its home position, means on said body portion stopping the roller in its home position, and means also on said body portion stopping said cam in its home position.

4. A swaging tool comprising a body portion provided with a handle, a fixed die supported in said body portion, an opposed movable die supported in said body portion, a roller supported in said body portion, a cam between said roller and said movable die, a handle for operating said cam, said roller being supported for rolling movement with said cam, a spring normally urging said roller into its home position, a roller backer adjustably supported in said body portion, and an adjustable connection between the body portion and the handle secured thereto and bearing against said roller backer for adjusting the position of said roller backer by rotation of said handle whereby the limit of approach of said dies upon closing movement of said handles may be adjusted.

5. A metal working tool comprising a body portion, a metal working element fixedly supported in said body portion, an opposed metal working element movably supported in said body portion, a cam engaging said movable element and mounted on said body portion for pivotal movement about an axis at right angles to the direction of movement of said movable element and for translatory movement in the direction of the movement of said movable element, a roller cooperating with said cam, an adjustable abutment for said roller mounted on said body portion, and means for operating said cam.

6. A metal working tool comprising a body portion, a metal working element fixedly supported in said body portion, an opposed metal working element movably supported in said body portion, a cam engaging said movable element and mounted on said body portion for pivotal movement about an axis at right angles to the direction of movement of said movable element and for translatory movement in the direction of the movement of said movable element, a roller cooperating with said cam, an adjustable abutment for said roller mounted on said body portion, a handle adjustably mounted in said body portion and engaging said abutment for adjusting the position of said abutment, and a handle for operating said cam.

OTTO J. BRATZ.
